INVENTOR.

Charles W. Bassett.

UNITED STATES' PATENT OFFICE.

CHARLES W. BASSETT, OF NEWTON, ASSIGNOR TO HALEY, MORSE & COMPANY, OF BOSTON, MASSACHUSETTS.

IMPROVEMENT IN CLOTHES-WRINGERS.

Specification forming part of Letters Patent No. 126,774, dated May 14, 1872.

Specification describing a new and useful Improvement in Clothes-Wringers, invented by CHARLES W. BASSETT, of Newton, in the county of Middlesex and State of Massachusetts.

My invention relates to that class of wringers that have their rolls connected together by gear or cog-wheels, which as heretofore constructed have been limited, as to the distance the rolls could be separated without being thrown out of gear, by the length of the tooth of the gear-wheels connecting the rolls; and the object of my invention is the production of a geared wringer, the rolls of which may be separated a distance nearly twice the length of the tooth of the gear without being thrown out of gear; in fact, to make it impossible to throw it out of gear; and it consists in the use of two gears of equal diameter, one upon the crank-end of either roll-shaft, the one upon the lower roll-shaft having a width of face equal to twice the width of the one on the upper roll-shaft into which it meshes, as well as into another gear of somewhat larger diameter mounted upon a fixed stud in a stand forming a part of the frame, said last-mentioned gear meshing into another gear of equal size and width of face with the one on the lower roll-shaft, and placed directly above the others and at such a distance that, when a large article is being passed through the rolls and the rolls are forced asunder thereby, the teeth on the upper side of the gear on the upper roll shall engage with the upper gear of the train before it is disengaged from the gear on the lower roll-shaft, and be driven thereby in the same direction, as will be described.

Figure 1 of the drawing is a front elevation of a wringer with my improvement attached, a portion of one end being shown in section; and Fig. 2 is a vertical section through the roll-shafts on line *x x* on Fig. 1 and showing the gearing in elevation.

A A are the standards, and B B are the tie-girts, altogether constituting the frame of the machine. C is the lower, and C' the upper roll; and D and D' are the boxes in which they have their bearings. E is a pressure-bar, resting at either end on the rubber spring F, and controlled by the set-screws G. H is a crank, secured to the lower roll-shaft C', all of the above being constructed in a well-known manner and is no part of my present invention.

Upon the end of the upper roll-shaft C' is mounted the gear-wheel *a*, which meshes into and is driven by the gear-wheel *b* of equal diameter, but double the width which is secured to the lower roll-shaft C'. I is a stand, secured to the standard A at its lower end, and provided with a stud, *c*, projecting inward therefrom, upon which is mounted the gear-wheel *d*, of the same thickness as the gear *a*, but of a diameter somewhat greater, and so located as to mesh into and be driven by the gear *b* on the lower roll-shaft C'. The stand I extends upward still further, and is connected to the frame at its upper end by the stud *e* and plate *f*. Upon the stud *e* is mounted, so as to revolve freely thereon, the gear-wheel *g*, of the same diameter and width of face as the gear *b*, and meshing into and being driven by the gear *d* revolving freely on the stud *c*. The gears *d* and *g* are simply idle-wheels—*i. e.*, though they revolve, they do no work so long as light or medium articles are passing through the roll—but when a large article like a heavy blanket or bed-spread is passed through the rolls, forcing them apart to so great a distance as to disengage the gear *a* from the gear *b*, the gear *a* will engage with the gear *g*, and power will be transmitted to the upper roll through the gears *d*, *g*, and *a*, the gear *b* being the driver at all times.

Although this arrangement of gearing was designed especially for operating the rolls of wringing-machines, it is obvious that it is equally applicable to other pressure-rolls, the distance between which is variable; therefore I do not wish to confine myself to its application to wringers.

Having thus described my improvement, what I claim as new, and desire to secure by Letters Patent of the United States, is as follows:

The within-described arrangement of gearing, consisting of the gears *a*, *b*, *d*, and *g*, constructed and applied as herein set forth, for the purpose of operating a pair of variable pressure-rolls, substantially as described.

Executed at Boston, this 29th day of January, 1872.

CHARLES W. BASSETT.
